DRINKING FOUNTAIN

Charles J. Deal, Santa Barbara, Calif.

Application June 12, 1939, Serial No. 278,783

1 Claim. (Cl. 119—74)

This invention relates to drinking fountains, and its general object is to provide a fountain for watering poultry and stock, that not only supplies an ample amount of continuous running 5 fresh water readily accessible for convenient drinking thereof, by both poultry and stock but provision is made in the construction of my fountain to take care of the overflow and for carrying the same away from the premises in which the 10 fountain is located, so that the floor or ground surface about the fountain is retained in a dry condition at all times, as such is desirable and essential from a sanitary standpoint, and especially with respect to chickens and like fowls, as 15 they must be kept as dry as possible in order to maintain them in a healthy condition.

A further object is to provide a drinking fountain of either a single or multiple form, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein 25 like characters denote like or corresponding parts throughout the several views, and in which:

Figure 1 is a view partly in section of the fountain which forms the subject matter of the present invention.

Figure 2 is a sectional view taken approximately on line 2—2 of Figure 1, looking in the direction of the arrows.

Figure 3 is a fragmentary top plan view.

Figure 4 is a detail sectional view taken through 40 the water inlet connection for my fountain.

Figure 5 is a top plan view of the multiple form.

Figure 6 is a fragmentary side elevation of the form of Figure 5.

Referring to the drawing in detail, and particularly to the form of Figures 1 to 4 inclusive, 45 it will be noted that it includes a hollow substantially cylindrical body 1 having open ends and exteriorly threaded for a portion of its length from said ends, to threadedly receive caps 2 and 3 for cooperation with the body to provide what may be termed an overflow well. The caps are laterally flanged to provide ground engaging and supporting members 4. The body is provided with an opening disposed centrally of the upper 50 portion thereof and is built up about the opening

to provide a ring portion or collar 5 having a beveled upper end or rim 6 rounded inwardly for directing the overflow water within the well as will be apparent upon inspection of Figure 1.

The caps have threaded openings therein and threadedly mounted in the opening of the cap 3 for disposal therethrough, is a pipe section 7 having its inner end terminating below the overflow opening of the body and threaded on the inner end of the pipe is a T-coupling 8 having its right angled branch directed upwardly and centrally of the overflow opening. Threaded within the upwardly directed branch of the T-coupling 8 is the reduced threaded portion 9 of a nipple formed on and depending from a cup 10, the latter being of semi-spherical formation and concentrically disposed with respect to the rim of the ring portion of the body, as best shown in Figure 1, and having its upper end disposed slightly above the ring portion. The branch of the T-coupling 10 is opposed to that connected to the pipe section 7 is closed by a plug 11.

The pipe section 7 is fixed to the cap 3 by lock nuts 12 and secured to the outer end thereof is a valve 13 for controlling the passage of water to 25 the cup. The outer end of the valve has connected thereto a swivel coupling 14, as best shown in Figure 4, for connecting a hose to the swiveled member thereof, for supplying water to the fountain from a suitable source, but of course it will 30 be understood that a pipe may be provided for that purpose, when the fountain is to be permanently fixed.

Threaded in the opening of the cap 2 is an outlet coupling 15 for the connection of a hose or 35 pipe thereto, for draining the water from the fountain and to a place remote therefrom, so that the floor or ground about the fountain will be free from water and retained in a dry condition.

From the above description and disclosure in the drawing, it will be obvious that when the fountain is in connection with a suitable source of water supply and the valve 13 is in open position, the water will enter the fountain through the pipe section 7 for disposal in the cup 10 which 45 is of sufficient depth for holding an ample supply readily accessible for convenient drinking therefrom by both poultry and stock, and from the cup, the overflow water enters the well about the space between the cup and ring portion or collar 50 5, and thence is drained from the well through the outlet coupling 15. The course of travel of the water, as set forth is clearly shown by the arrows in Figure 1.

The multiple form of my fountain as shown in 55

Figures 5 and 6, is similar in many respects to the form of Figures 1 to 5 inclusive, and the only difference between the two forms, is that the body 16 of the multiple form is of elongated cylindrical formation to make provision for a plurality of water receiving cups 17 which may be carried by a plurality of T-couplings connected together by short pipe sections or nipples. In any event, the water is supplied to each of the cups 17, and it will be obvious that the form of Figures 5 and 6 is desirable where it is necessary to water a large quantity of poultry or stock. While I have illustrated the multiple form as including six cups, it will of course be understood that it may be made to include any number of cups.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A drinking fountain comprising a horizontally disposed hollow cylindrical body having open ends, caps closing said ends, flanges formed on the caps and extending laterally therefrom to provide ground receiving and supporting means for the fountain, said body and caps providing an overflow well and the body having an opening in the upper portion thereof, a collar formed on the body and rising therefrom about the opening, a pipe section secured to and extending through one of said caps, hollow water receiving and drinking means connected to the pipe section for disposal through the opening and collar in spaced relation with respect thereto to provide a passage for the overflow water from the drinking means into the well, an outlet coupling secured to the other cap and threaded to receive means for draining water from the well to a place remote from the fountain, and means for controlling the passage of water to the pipe section. 5 10 15 20
